FIG. 4.

INVENTOR

Thomas E. White
By
Charles N. Butler
ATTORNEY.

UNITED STATES PATENT OFFICE.

THOMAS E. WHITE, OF PHILADELPHIA, PENNSYLVANIA.

SOOT-BLOWER.

984,871.

Specification of Letters Patent. Patented Feb. 21, 1911.

Application filed July 26, 1910. Serial No. 574,003.

To all whom it may concern:

Be it known that I, THOMAS E. WHITE, a citizen of the United States, residing at Philadelphia, in the county of Philadelphia 5 and State of Pennsylvania, have invented certain Improvements in Soot-Blowers, of which the following is a specification.

My invention is designed to provide improved means for clearing boilers of soot. 10 My improvements, in their preferred construction, comprise several groups of nozzles separately movable through a boiler casting, into operative position, by the pressure of the fluid used in blowing the soot and 15 means for automatically withdrawing the nozzles when the flow of fluid is cut off.

The characteristic features of my improvements are disclosed in the following description and the accompanying drawings 20 in illustration thereof.

In the drawings, Figure 1 is a side elevation of a boiler having my improvements applied thereto; Fig. 2 is an enlarged sectional view taken on the line 2—2 of Fig. 25 1; Fig. 3 is an enlarged top sectional view, representing details of construction, and Fig. 4 is a sectional view of the end of a nozzle.

The apparatus, as illustrated in the drawings, comprises the casing 1 which incloses the boiler having tubes 2, the casing being provided with vertical chambers 3 extending transversely to the tubes and separated therefrom by diaphragms 4. The boiler has 35 the top of its drum 5 connected with a duct 6, controlled by a valve 6', which carries steam to the branch ducts 7, controlled by valves 7', whence it is distributed through the headers 8 to the ducts 9, controlled by 40 valves 9'. The respective ducts 9 are provided with cylindrical terminals 9' in which are disposed tubes 10 adapted to reciprocate therein. Each of the tubes 10 is connected by a header 11 with parallel 45 nozzles 12 which are adapted to move through the corresponding diaphragm 4. Each nozzle has a plug 12° in the forward end thereof and the diverging passages 12' therein, by which the fluid discharged there- 50 through is spread. Coiled springs 13 are disposed between the respective diaphragms 4 and the corresponding headers 11, whereby the nozzles are normally held in the withdrawn position shown in Fig. 3. When, 55 however, the valves 6' and 7' are opened so that steam can flow from the drum 5 to

the header 8, upon opening a valve 9' the steam flowing through the corresponding duct 9 will exert an unbalanced pressure against the inner ends of the tubes 10 and 60 the plugs 12°, the nozzles being thereby carried through their diaphragm. Steam will now be discharged through the nozzles of the set or sets which have been carried inwardly so that their forward ends 65 extend between adjacent tubes and will discharge diverging jets that will blow off the soot effectively.

As each of the chambers contains several sets of nozzles adapted to be operated independently by opening the corresponding valves 9', it will be understood that the groups of nozzles can be caused to blow in sequence and the blowing can be carried on progressively through the several passes 75 from the grate chamber 14 to the flue 17. The arrangement shown is adapted for use with a boiler having baffles 15 disposed transversely to the tubes and forming vertical passes 16 into each of which three sets 80 of nozzles 12 discharge so that cleaning can be effected by blowing progressively from the inlet to the first pass to the outlet of the last pass. When the valves 7' are closed and the valves 9' are open, check valves 18, 85 closed by the steam pressure and automatically opening when the steam is cut off, permit air to be drawn through the tubes 9 and nozzles 12, whereby the latter are dried out and corrosion therein prevented. 90

Having described my invention, I claim:

1. In a soot blower, a duct having a cylindrical terminal, a tube adapted to reciprocate in said terminal, a tubular header fixed to said tube and a set of nozzles fixed 95 to said header, said nozzles being provided with diverging discharge passages.

2. In a soot blower, the combination with a boiler having a casing and successive passes therein, of several nozzles communicating through said casing with each of said passes, and means whereby fluid can be discharged through said nozzles in succession.

3. In a soot blower, the combination with 105 a boiler having tubes and a casing having chambers extending transversely to said tubes, of several sets of nozzles disposed in each of said chambers, and means whereby each set of nozzles can be reciprocated independently of the others.

4. In a soot blower, the combination with

a boiler having tubes, a drum, and a casing containing chambers extending transversely to said tubes, of several nozzles disposed in the respective chambers, a duct connected with the steam space of said drum, and valved pipes connecting said duct with the respective nozzles.

5. In a soot blower, the combination with a boiler having tubes, a wall having a chamber, and a diaphragm in said chamber, of several sets of nozzles adapted to be reciprocated through said diaphragm, several

steam pipes, means for connecting the respective steam pipes with sets of said nozzles, and means whereby each set of nozzles 15 is reciprocated.

In witness whereof I have hereunto set my hand in the presence of the subscribing witnesses, this 23 day of July, 1910.

THOMAS E. WHITE.
